CLAIM

I claim the ornamental design for an adjustable finger stylus, as shown and described.

DESCRIPTION

FIG. 1 is a side perspective view of an adjustable finger stylus showing my new design;

FIG. 2 is a side elevational view thereof;

FIG. 3 is a perspective view thereof with the attachment strap in an opened position;

FIG. 4 is a bottom plan view of FIG. 3; and,

FIG. 5 is a front elevational view of FIG. 3.
